UNITED STATES PATENT OFFICE.

CHARLES J. CALEY, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

LOCK AND LATCH OPERATING MECHANISM.

No. 806,776.

Specification of Letters Patent.

Patented Dec. 12, 1905.

Application filed March 9, 1905. Serial No. 249,154.

To all whom it may concern:

Be it known that I, CHARLES J. CALEY, a citizen of the United States, residing at New Britain, county of Hartford, and State of Connecticut, have invented certain new and useful Improvements in Lock and Latch Operating Mechanism, of which the following is a full, clear, and exact description.

My invention relates to improvements in lock and latch mechanism, and particularly to bearings for a knob-and-spindle construction.

The object of the invention is to provide mechanism for operating a lock or latch which shall be simple in construction, applicable even in places where the spindle-passage is arranged at a slight angle to the door, substantially frictionless, and capable of compensation for slight maladjustment.

The invention consists in improvements the details of which are illustrated in the accompanying single sheet of drawings. A rose-plate or thimble forms a long guide-tube for the knob-shank and is provided with a yielding antifriction device at the outer end.

The knob-spindle is loosely pivoted to the knob-shank and provided with a screw-threaded portion for the reception of what is commonly termed a "screwless-knob construction."

Figure 1 is a section and side elevation of a construction embodying the improvements of my invention. Fig. 2 is an end view of the rose-plate or thimble with the antifriction device. Fig. 3 is an end view of the spindle. Fig. 4 is a detail of a spring-plate for affording a yielding bearing for the antifriction device.

1 indicates a rose-plate or thimble, which may be attached directly or indirectly to the door.

2 indicates an escutcheon-plate, and 3 indicates a fragment of a door.

The outer end of the thimble is provided with an annular cavity in which is arranged a ball-retainer 4. 5 represents one of a series of balls mounted in this retainer.

6 is a spring-plate mounted in the cavity back of the ball-retainer for normally pressing it outward evenly.

7 is a small flange or inwardly-turned rim of the thimble which is turned in to hold the ball-retainer in place and prevent it from ex-

tending outward beyond the position shown in Fig. 1.

8 is a knob, which may be of any suitable construction.

9 is the shank of the knob, which is formed with a cavity or recess in its end.

10 is a convexly-curved conical bearing carried by the knob-shank and abutting against the shoulder 11 on the knob. This shoulder 11 also serves as a stop to limit the inward adjustment of the knob.

12 is a knob-spindle formed of suitable material and loosely fitted in the recess in the end of the knob-shank.

13 is a pin carried by the knob-shank which passes through a hole in the knob-spindle, which is of somewhat larger diameter than the pin. The spindle therefore has considerable play, as indicated in Fig. 1.

14 represents a series of screw-threads on the opposite end of the spindle 12, to which is attached the adjusting and clamping members of a screwless-knob construction of any suitable type.

By this invention the knob is provided with a strong support to prevent prying off the rose or thimble by reason of the long guiding-bearing which it has. The yielding antifriction device serves to give a uniform bearing for the knob-and-spindle construction at all times within reasonable adjustment of the spindle. The spindle itself being loosely carried by the knob-shank may coöperate with the usual roll-backs, even though they are somewhat out of alinement, and without binding the knob or shank.

Other advantages will be apparent to those skilled in this art.

What I claim is—

1. A lock and latch fitting comprising a long tubular thimble, a spring-pressed antifriction device carried in the outer end thereof, a knob, a bearing therefor, coöperating with said spring-pressed antifriction device, and a shank extending therefrom and into said thimble and guided thereby.

2. A lock and latch fitting comprising a long tubular thimble, a spring-pressed antifriction device carried in the outer end thereof, a knob, a bearing therefor coöperating with said spring-pressed device, a shank extending therefrom and into said thimble and

guided thereby, and a spindle having a loose pivotal connection with said knob-shank and a screw-threaded portion at its opposite end for the purpose specified.

- 5 3. A lock and latch fitting comprising a thimble, a yielding antifriction device carried thereby, a knob and shank having a bearing for coöperating with said antifriction device, a spindle having a screw-threaded portion at 10 one end and means for loosely pivoting said spindle at the other end to said shank.
4. In a knob-and-spindle construction the combination of a rose-plate or thimble form-

ing a long tubular guide, an antifriction device arranged at the outer end thereof, a knob, 15 a shank, a bearing coöperating with said antifriction device, said shank projecting into and closely fitting in the tubular guide portion of said thimble or rose-plate, a spindle, and means for loosely pivoting said spindle in said shank 20 for the purpose specified.

CHAS. J. CALEY.
